CLAIM

The ornamental design for a non-reciprocating side charging upper receiver, as shown and described.

DESCRIPTION

FIG. 1 is an isometric view of the non-reciprocating side charging upper receiver, which embodies our design, shown in use attached to environmental features;

FIG. 2 is a back isometric view of the non-reciprocating side charging upper receiver;

FIG. 3 is a front view of the non-reciprocating side charging upper receiver;

FIG. 4 is a back view of the non-reciprocating side charging upper receiver;

FIG. 5 is a side view of the non-reciprocating side charging upper receiver;

FIG. 6 is an opposite side view of the non-reciprocating side charging upper receiver; and,

FIG. 7 is a top plane view of the non-reciprocating side charging upper receiver.

The broken lines in the drawings are used to illustrate unclaimed environmental features that form no part of the claimed design.
